UNITED STATES PATENT OFFICE.

WILLIAM G. RICHARDS, OF BOSTON, MASSACHUSETTS, ASSIGNOR, BY MESNE ASSIGNMENTS, TO THE AMERICAN STEEL WHEEL COMPANY, OF NEW JERSEY.

MOLDER'S FLASK.

SPECIFICATION forming part of Letters Patent No. 451,577, dated May 5, 1891.

Application filed July 14, 1890. Serial No. 358,655. (No model.)

To all whom it may concern:

Be it known that I, WILLIAM G. RICHARDS, a citizen of the United States, residing at Boston, in the county of Suffolk and State of Massachusetts, have invented certain new and useful improvements in Molders' Flasks, of which the following is a specification.

This invention relates to flasks for casting car-wheels and like articles by the method of filling the mold from the under side thereof, the object being to furnish a flask for such purposes having means for holding in place the cores and in which the several parts may be readily assembled and taken apart.

15 My invention is in the nature of an improvement on the molder's flask described and claimed in my application, Serial No. 358,654, filed July 14, 1890.

In the drawings accompanying and forming a part of this specification, Figure 1 is a front elevation of a flask embodying my present improvements. Fig. 2 is a central vertical section of the same. Fig. 3 is a plan view of the under side of a portion of the bottom board with the removable plate thereon. Fig. 4 is a cross-section in the line *a-a* of Fig. 3, as seen in the direction of the arrow. Fig. 5 is a plan view of my improved flask, a portion of the pouring-head being broken away and the 25 "chill" 10 not being shown. Fig. 6 is a plan view of the under side of the bottom board. Fig. 7 is a plan view of the pouring-head. Fig. 8 is a sectional view of one of the plugs carrying the anchor-rods.

35 Similar characters designate like parts in all the figures.

My improved flask consists of the nowel or "drag" 8, the chill 10, resting on said nowel-frame and having the usual dowel-pins 35 for retaining the said parts in place relative to each other, and the cope 9, which rests on the said chill and is removably secured thereto by the bolts 36, which bolts pass through ears 62 and 64, formed on said chill and cope, respectively, and are furnished with the keys or wedges 37. The nowel part 8 of the flask is set on the usual bottom board 52, and is properly located thereon by the dowel-pins 53, which are fixed in ears 75, formed on the lower 45 frame 8 of the flask.

In practice the bottom board 52, and also

the partition-walls 46, may be perforated with numerous small holes in a well-known manner to increase their hold upon the material of the mold. For stiffening said bottom board, 55 and also for supporting the same at a suitable distance above the foundry-floor, it is provided with a circular rim 71, extending nearly around the board near the periphery thereof. Within said rim 71 said bottom board is further stiffened by ribs 72 and 73, which I make of slightly less depth than the rim 71. From the rib 72 and extending out to the margin of the bottom board I make an opening 62, from whose edges depend two parallel ribs 65 60 and 64. Said opening 62 is closed by the bottom plate 65, which is removably held in place under said ribs 63 and 64 by means of clamps, also removably affixed to said bottom board. The preferred construction of these 70 details is shown in Figs. 3, 4, and 6.

The bottom plate 65 has side flanges 84 and 85 on the opposite sides thereof, respectively. Clamps 86 and 87 are affixed to the bosses 88 and 89 by screws 90 and project under said 75 flanges 84 and 85, respectively. In practice these several parts are so fitted up that the plate 65 may be removed by sliding the same away from the rib 72 until the flanges 84 and 85 are out of engagement with said clamps, 80 when the plate may be taken off; but if leakage of molten metal or other obstruction should prevent this method of removing said plate, then by removing said screws 90 the bottom plate may be taken off without sliding it endwise. The space 62 above said bottom plate and between said ribs 63 and 64 is provided 85 wherein to form the runner 76, which leads through the vertical passages 100 and 102 into the under side of the mold, which, as shown 90 in Fig. 2, is filled by the car-wheel W, there shown in section with the arch-core therein.

As shown in Fig. 2, the cope part 9 of the flask is provided with a number of radial partitions 46 and with the central ring 47 for supporting the sand of the cope. A number of anchor-holders 48 (of which four are shown in the drawings) are screwed into the partitions or ribs 46, and are bored to receive the wires or anchor-rods 49, by which the arch-core 50 is held down during the filling of the mold, said rods being secured by wedges 51,

which pass through said holders tangential to said rods.

In practice, after making the mold in substantially the usual manner, the core 50 being set in place and the mold closed, the rods 49 are put in and firmly pushed down through the holders 48 and the perforations in the ribs 46 against said core, when the wedges 51 are firmly tightened by driving them with a light hammer. The mold being filled, the metal of the wheel W firmly incloses said rods, which may afterward be cut off, leaving the ends thereof remaining in the casting.

Owing to the unavoidable presence of sand, wedges for holding the rods 49 are found preferable to bolts, screws, or other clamping devices, and for said wedges I find well-formed cut nails to be suitable, since these are regular in size, of the proper taper, and inexpensive, besides being always at hand in foundries generally. The central rim 47 of the cope-frame 9 is divided at two points 97 97 to avoid breakage from expansion when the mold is highly heated by the contained molten metal, which expands the central part much more rapidly and sooner than it expands the outer rim. Each half portion of said rim 47 is connected integrally with two of the ribs 46, thereby securing the strongest construction permissible under the circumstances. The space between the main ribs 46 is divided by a series of thinner ribs 96, which extend inward from the rim 9 nearly to the circle 47 for supporting the sand of the cope.

The pouring-head C is formed in two parts 66 and 68, and is held together at the upper end by the clamp-ring 54, which fits on the inclined ribs 55, formed on said parts. For properly locating said parts 66 and 68 the one on the other the dowel-pins 38 38 are provided. A flange 39 is formed on the lower end of the pouring-head C, whereby to hold the said head in place on the flask. When said head is set in place on the flask, as in Figs. 1, 2, and 5, the said flange 39 rests against the abutment or flange 56 of the bottom board 52 and between the lugs 57 and 58 of said board. The upper part of the flange 39 overlaps and rests on top of the said lugs, as shown in Figs. 1 and 5, thus supporting the weight of the head C on the surfaces 98 98, Fig. 5.

To lock the head C in place I use a pair of wedges 59, which stand in the notches 99 99 and are driven firmly between the flange 39 of the head and the ends or hooks 60 and 61 of the lugs 57 and 58, respectively. (See Fig. 5.) Said wedges 59 may be separate; but I prefer the construction shown in the drawings, wherein the wedges are firmly connected by the yoke 59', which extends over the curved lower end of the head C outside of the flange 39. By means of this connecting yoke or bar both wedges are readily operated at once, being "driven home" by a blow on the bar and readily removed by a bar inserted under said yoke.

In making the mold the nowel and the cope are handled and made up in the usual way and assembled with the chill in place between them, the core being properly set, as above mentioned, and the nowel having the passage-way 76 for inflowing metal and leading from the vertical face 77 to the under side of the mold. The pouring-head C is properly lined with sand, as at 78, leaving a passage at 80, which, when said head is set in place, as shown, connects with the passage 76. After the mold is poured and the metal is slightly cooled the wedges 59 are pried out and the pouring-head forcibly separated from the nowel, breaking the metal of the "runner" at the joint 77. The ring 54 is then knocked off, allowing the two parts 66 and 68 of the head C to separate and the contained sand and metal to drop out. The remaining operations of opening the mold and removing the casting will be understood from the drawings and preceding description without further explanation.

Having thus described my invention, I claim—

1. In a molder's flask, the combination, with the nowel and the bottom board provided with a pouring-head at one side thereof, said bottom board having an opening extending from the pouring-head along under the runner, of the bottom plate under said bottom-board opening, and means, substantially as described, removably holding in place said bottom plate.

2. In a molder's flask, the combination, with the bottom board having the opening 62 and the depending ribs 63 and 64 at the side of said opening, of the bottom plate 65 and clamps removably fixed to the bottom board 105 and engaging the said bottom plate.

3. In a molder's flask, the combination, with the bottom board having an opening with depending ribs on either side thereof, of the bottom plate having the short side flanges 84 110 85 and clamps removably fixed to the bottom board and engaging said flanges, and a stop limiting the longitudinal movement of said bottom plate under said clamps.

4. In a molder's flask, the combination, with the bottom board having the flange 56 and the lugs 57 58, said lugs being constructed to engage pouring-head-locking devices, of the pouring-head C, having the flange 39 constructed to bear against flange 56 and to rest 120 on said lugs, whereby the weight of said head is sustained by said lugs, and wedges engaging between the lugs and pouring-head flange, whereby the pouring-head is locked in place.

5. In a molder's flask, the combination, with the bottom board having a vertical seat for the pouring-head and having the horizontal oppositely-disposed lugs on either side of said pouring-head seat, of the pouring-head constructed to rest against said seat between said lugs, and locking devices, substantially as described, engaging said lugs and bearing against the pouring-head, whereby said pouring-head is held in place against its said seat, and

whereby on removal of said locking means the pouring-head is free to be removed.

6. In a molder's flask, the combination, with the bottom board having the flange 56 and the lugs 57 and 58, said lugs being constructed to engage the pouring-head-locking devices, of the pouring-head C, having the flange 39, constructed to bear against flange 56 and to rest on said lugs, whereby the weight of said head is sustained by said lugs, and wedges engaging between the lugs and pouring-head flange, whereby the pouring-head is locked in place.

7. In a molder's flask, the combination, with the bottom board having the flange 56 and the lugs 57 58, provided with hooks 60 61, of the pouring-head C, having the flange 39 fitting between said lugs and bearing thereon, and the wedges engaging between said hooks and the flange 39 to hold the pouring-head against flange 56, whereby said head is removably fixed in place.

8. In a molder's flask, the combination, with the bottom board constructed, substantially as described, to receive the pouring-head, of the pouring-head constructed, substantially as described, to rest against said bottom board, and connected wedges, one on either side of said pouring-head at the lower end thereof, said wedges engaging the bottom board and pouring-head to lock the same together and being united by a bar, whereby said wedges may be driven in place and removed.

9. In a molder's flask, the combination, with

the bottom board having the flange 56 and 35 having lugs 57 58, each hook-provided, of the pouring-head C, formed in two parts 66 and 68 and constructed to engage between said lugs and bear on said flange 56, means uniting the upper ends of said pouring-head parts, 40 and locking devices, substantially as described, engaging the hooks of said lugs for clamping said head in place, the lower ends of the pouring-head parts being held together by engaging between said lugs. 45

10. In a molder's flask, the combination, with the nowel and the cope-frame and the core set on the nowel, of anchor-rod holders, substantially as described, fixed to the cope-frame over perforations therein, anchor-rods 50 extending through said holders and perforations, and wedges crosswise to the anchor-rods in said holders, whereby said rods are fixed in place to resist the rising of the core during the filling of the mold. 55

11. In a molder's flask, the combination, with the cope-frame outer ring, of the inner ring divided into segments and a pair of ribs joining each segment with the outer ring, said ribs joining the segment near the ends thereof, and ribs extending inward from the outer ring and located between the segment-supporting ribs, said intermediate ribs not joining said segment. 60
